(57) **CLAIM**

(22) Filed: **Dec. 18, 2002**

The ornamental design for an actuator body for an inhalation device, as shown and described.

(51) LOC (7) Cl. **29-02**

DESCRIPTION

(52) U.S. Cl. **D24/110**

FIG. 1 is a perspective view of an actuator body for an inhalation device. The broken lines are for illustrative purposes only and form no part of the design;

(58) Field of Search D24/110, 110.5,

FIG. 2 is a side view thereof;

D24/164; 128/200.24, 200.23, 200.22, 200.14,
200.12, 203.12, 203.14, 203.15, 203.25,
204.2; 222/162, 153.11, 192, 183, 509,
321.7, 321.8, 321.9

FIG. 3 is a front view thereof;

(56) **References Cited**

FIG. 4 is a top view thereof; and,

U.S. PATENT DOCUMENTS

FIG. 5 is a bottom view thereof.
